(57) **CLAIM**

The ornamental design for a nail clipper organiser, as shown and described.

DESCRIPTION

FIG. 1 is a front, top perspective view of a first embodiment of a nail clipper organiser, showing my new design;

FIG. 2 is a rear, bottom perspective view thereof;

FIG. 3 is a front elevation view thereof;

FIG. 4 is a rear elevation view thereof;

FIG. 5 is a left side elevation view thereof;

FIG. 6 is a right side elevation view thereof;

FIG. 7 is a top plan view thereof;

FIG. 8 is a bottom plan view thereof;

FIG. 9 is a front, top perspective view of a second embodiment of FIG. 1, the only difference being the broken line configuration on the front wall of the nail clipper organiser, it being understood that all other surfaces are the same as those of the first embodiment;

FIG. 10 is a front, top perspective view of a third embodiment of FIG. 1, the only difference being the broken line configuration on the front wall of the nail clipper organiser, it being understood that all other surfaces are the same as those of the first embodiment; and,

FIG. 11 is a front, top perspective view of a fourth embodiment of FIG. 1, the only difference being the broken line configuration on the front wall of the nail clipper organiser, it being understood that all other surfaces are the same as those of the first embodiment.

The broken lines in the figures illustrate portions of the nail clipper organiser that form no part of the claimed design.
